UNITED STATES PATENT OFFICE.

ANDREW KANELL, OF CHICAGO, ILLINOIS.

SHOE-STRETCHING DEVICE.

Application filed May 13, 1927. Serial No. 190,992.

My invention relates to shoe-stretching devices. One of the objects of my invention is to provide a simple, durable, inexpensive and positively-acting shoe-stretching device 5 which is readily adaptable to stretching the toe-portion of the shoe and to stretching the shoe as a whole lengthwise, these stretching movements being carried out separately or simultaneously as desired. To this end I employ a toe-stretching unit comprised of freely adjustable sections joined together by a horizontally-acting toggle; a heel or rear unit joined to a portion of the toe-unit by flexible and vertically acting toggle members 15 which are adapted to flex laterally during the adjusting movements of the toe-unit section; and means for adjusting these units relative to each other and the toe-sections relative to each other, the entire arrangement being 20 such that all of the operating parts are free to readily adapt themselves to the adjusting movements without interfering one with the other.

A further object is to provide means for 25 holding the separated toe-sections in longitudinal alignment during the various adjusting movements.

Other objects are to provide means for adapting the stretching device to shoes, and 30 the like, of varying lengths so that full lengthwise stretching adjustments may be obtained in all instances; the provision of means for positively retaining, positioning and guiding the means for adjusting the toe-unit sections; and the provision of means for locking and holding the stretcher parts in 35 their adjusted position so as to maintain the shoe, or the like, in the adjusted or stretched condition over any desired length of time 40 without the attention of the operator.

Other and further objects will become apparent as this description progresses and by reference to the drawing wherein,—

Figure 1 is a top plan view, partially in 45 section, of a shoe-stretching device embodying my invention.

Fig. 2 is an elevated view, partially in section, of a half-portion of the structure shown in Fig. 1, the adjusting and control devices 50 being shown.

Fig. 3 is a perspective view of means for adapting the stretching device to shoes, and 55 the like, of considerable length, so that the full benefit of the lengthwise adjustment may be obtained in all instances.

While my invention has been referred to as being applied to shoe-stretching devices, it will be understood that the term "shoes" is used in its general and broad sense and includes slippers and similar articles which 60 may be used for covering and protecting the feet.

Referring now to the drawing, the structure shown therein may comprise a toe-unit A and a heel or rear unit B. The toe-unit A 65 is formed of two separate sections 4 and 5, which have their outer portions approximating the shape of the inner toe parts of the shoe. These sections are of such shape and length as to extend into the toe of the shoe to 70 the desired extent and they are provided with slots or recesses 6 and 6^a, respectively, at their forward ends. Links 7 and 8 of a toggle are pivoted in the recesses 6 and 6^a as at 9 and 10, such links being pivotally connected 75 together at 11 to complete the toggle. These toggle links permit the sections 4 and 5 to spread laterally as a whole as well as permitting their free rear portions to spread in 80 a fan-like manner and furthermore the links are, preferably, formed of thin flexible metal which will permit the toe-sections 4 and 5 to readily adjust themselves to the conditions in 85 the toe of the shoe, while the toe-sections themselves are, preferably, formed of some desired kind of wood. However, it is to be understood that, if desired, these sections may be formed of some light metal or fibre material, or some other desired material, without departing from the spirit and scope of my 90 invention. When the toe-sections 4 and 5 are assembled together as shown in Figure 1, the recesses 6 and 6^a form an internal chamber in 95 which the toggle operates which permits of the lateral spreading action of the toe-sections without bringing any parts which might injure the shoe in contact with the interior part of the shoe. The toggle insures 100 positively the spreading action within definite and desired limits and also properly insures the return of the sections to their proper position when the device is operated to bring the sections back to the position shown in Fig. 1, after an adjustment has been made.

Referring to Fig. 2, it will be seen that the 105 rear portion of the toe-sections 4 and 5 is provided with a wedge-shaped chamber 12 which is adapted to receive the spreader 13. The chamber 12 is formed by providing in each of the toe-sections a recess 14 which ap- 110

proximates in shape the side of the wedge-shaped spreader 13. However, the recesses 14 are longer than the spreader 13 so as to permit of movement of the spreader back and forth therein. Each of the recesses 14 is provided with a longitudinal slot 15 which extends beyond such recesses toward the front end of the toe-sections, the object of these slots being to receive a longitudinally and 10 centrally disposed guiding ledge 16 extending around the wedge-shaped spreader 13. With the toe-sections assembled in the position shown in Fig. 1, the recess 12 is therefore provided with opposite guideways or 15 slots 15 carrying the ledge 16 of the spreader 13 whereby such spreader is positively positioned and guided during its movement back and forth in the spreader chamber 12, during the toe-stretching adjustment. The slots 15, 20 in extending beyond the chamber 12, as shown in Fig. 1, provide an extended guide-way which guides the spreader 13 in its movement beyond the chamber 12 towards the front end of the toe-unit during extended stretching 25 adjustment. The means for adjusting the spreader 13 and toe-sections will be described later.

The heel or rear unit B is formed of two sections 17 and 18, which are, preferably, 30 fixed together by one or more screws 19, as illustrated in Fig. 2. The rear end of this unit approximates the shape of the heel of the shoe while its front end is V-shaped as at 20. The rear portion of the toe-unit has a 35 complementally-shaped surface 21 whereby the units A and B may be moved and guided together and held in that position so as to bring the structure as a whole within small limits, which may be desirable in making certain adjustments in certain sizes of shoes as is obvious.

The interior of the unit B is provided with a hollow portion adapted to receive a screw-adjusting nut 22 having side extensions 23 carried in the heel sections 17 and 18 to hold the same fixed in place. A screw-rod 24 having a handle 25 is adapted to pass through the nut 22 and extend through the heel unit B and is connected to the spreader 13 as shown in Fig. 2. The connection of this rod 24 with the spreader 13 is accomplished by providing such rod with a reduced unthreaded end portion 26 which passes through the rear of the spreader into an opening through the rear portion thereof, the end portion 26 being secured for rotation relative to the spreader by washer 27 which is locked in place by the screw 27^a. By turning the handle 25 in a clockwise direction, the spreader 13 is advanced in the chamber 12 to spread the sections 4 and 5, both laterally and in a fan-like fashion and a reverse movement of the handle 25 withdraws such spreader to permit the toe-sections to be moved together to the position shown in Fig. 1.

The forward portion of the heel unit B is provided with a rectangular-like recess 28 adapted to receive the rear portion of the spreader 13 when the units A and B are moved toward each other either with their complementary surfaces 20 and 21 together or in close proximity; otherwise, with the spreader 13 in a somewhat extended position, a movement of the units together might spread the sections 4 and 5 to some degree which might not be desirable under certain conditions. In such case the spreader is moved by the handle 25 as above described.

It is desirable that the units have an operative connection to facilitate handling of the same and to aid in their adjustment. I, preferably, accomplish this connection by means of vertically carried toggles 29 and 30 (Fig. 1) formed of thin flexible metal. These toggles are comprised of arms 31 and 31^a hinged to the respective toe-sections by the pins 31^b, and arms 32 and 32^a hinged to the heel-unit by the pins 32^b, the arms 31 and 31^a and 32 and 32^a being pivotally joined at 33 and 33^a to complete the toggle. In order to accomplish the desired operation of these toggles during the movements of the units A and B toward and from each other without interference, I mount the same in slots 34 in the respective heel and toe sections, the lower part of the arms of the toggle being, preferably, pivoted at the bottom of these slots which extend and open through the upper part of the respective sections. Still further, due to the fact that the parts of these toggles are made of thin, flexible material and they are not joined together, they permit of the above described movements of the toe-sections 4 and 5 in a free and flexible manner as the spreader 13 is moved back and forth.

To accomplish the lengthwise adjustment of the stretching unit, I employ an operating unit comprised of a rack 35 and pinion 36, the rack being connected to the toe-section 4 by the bracket member 37. The pinion 36 is carried on a shaft 38 which is journaled between the heel unit sections 17 and 18 and the block 39 which carries the rack 35. The shaft 38 is provided with an extension 40 having a handle 41 which is adapted to rotate the pinion 36 to move the rack forward or backward to adjust the spreader 13.

In order to lock the rack 35 in its adjusted position and, consequently, the units A and B in their adjusted position, I provide a spring-pressed latch member 42 adapted to engage in the notches 43 of the rack. A spring 44 is mounted upon the rack block 39 in such a way as to yieldingly hold the end 42^a of the latch outwardly and its other end in yielding engagement with the registering notch 43. As the handle 41 is moved to move the racks 35 back and forth, the latch 42 will yield sufficiently to permit their action, but at other times, and when the adjustment has been

made, the latch will hold the rack in its adjusted position and, consequently, the units A and B in their adjusted position.

In order to provide for the greatest flexibility and ease of adjustment of the toe-sections 4 and 5, it is desirable that they be joined only by the toggle links 7 and 8 as hereinabove described. Furthermore, as stated above, the rack 35 for effecting the lengthwise adjustment is connected to the toe-section 4 only so as not to interfere with the lateral movement of the toe sections and, if not otherwise provided for, there would not be uniform, and desired simultaneous movement of the sections 4 and 5 during the lengthwise adjustment above described. To effect such simultaneous and uniform movement of these sections during this adjustment, I provide a follower device 45 which is rigidly secured to the section 4 and which extends laterally across and behind the other toe-section 5. It is obvious that as the rack 35 is moved forwardly for lengthwise adjustment, the toe-sections, which are practically floating sections, are moved forwardly simultaneously.

There may be some instances where it is desired to stretch shoes which are of exceptional length. In that case, in order to secure the full benefit of stretching adjustments, I employ an extension device 46, preferably, of the construction shown in Fig. 3. This extension piece has a curved face 46^a adapted to fit over the rear of the heel B, as shown in Fig. 2, and a rear portion 46^b approximately the shape of the heel of the shoe. The part 46 very efficiently serves as a heel unit extension means in a manner shown in Fig. 2 in dotted lines.

It is believed that the operation of this structure is obvious from the foregoing and it may be stated generally as follows: When it is desired to stretch the toe of the shoe, the toe unit A is inserted in that portion of the shoe to the desired extent and the handle 25 is then turned in a clockwise direction. This action moves the spreader 13 forwardly, and, in an obvious manner, causes the spreading and flaring action to take place between the sections 4 and 5 to an extent dependent on the extent of movement of the handle 25. In order to make the lengthwise stretching adjustment, the entire structure is inserted in the shoe with the heel portion resting against the heel of the shoe on the interior and the toe unit extending into the toe of the shoe. The structure may be first preliminarily adjusted to the size of the particular shoe which is to be stretched. After the parts have been so inserted, the handle 41 is turned in a clockwise direction and the units A and B separated. This action may take place to a desired extent dependent upon the extent of movement of the handle 41. At the same time, if a toe-stretching action in a lateral

direction is desired, the handle 25 may also be moved and the double adjustment accomplished simultaneously.

From the foregoing it is obvious that I have produced a highly efficient, durable, and positively-acting shoe-stretching apparatus which as a whole is very flexible and easy to operate. Although I have shown only one specific form of my invention, it will be understood that various changes and modifications may be resorted to without departing from the spirit and scope of my invention as defined by the following claims.

I claim:

1. In a shoe-stretcher, a toe-stretching unit so comprising two mated sections approximating the shape of the toe of the shoe, each said section having a recess in its forward end to form an interior cavity in the joined sections, a toggle connected to the sections and carried in said cavity and forming the sole connection between said sections, each said section having another recess formed in its end opposite said first recess and forming an interior wedge-shaped cavity in the joined sections, guideways in the walls of said latter cavity and extending forwardly beyond the same, a wedge-shaped member in said latter cavity and having a peripheral flange carried in said guideways, and means for moving said member forwardly in said latter cavity to separate said sections and flare their rear ends.

2. In a shoe-stretcher, a toe-stretching unit comprising two mated sections approximating the shape of the toe of the shoe, an enclosed toggle connected to one end of said sections and forming their sole connection, a wedge member carried in a cavity at the other end of said sections, guide means extending through and beyond said cavity for guiding said member, and means for moving said member forwardly in and beyond said latter cavity to separate said sections and flare their rear ends.

3. In a shoe-stretcher, a toe-stretching unit comprised of two sections connected by a horizontally disposed toggle, a heel unit, a vertically disposed toggle connecting each of said sections to said heel unit, said latter toggles being comprised of flexible metal members, a spreading member adapted to be moved between said sections, an adjusting screw attached to said member and carried by said heel unit for moving said member to adjust said sections laterally and in fan-like fashion, means carried by said heel unit and connected to said toe-stretching unit for adjusting said latter unit longitudinally, and a latch for locking said units in their longitudinally adjusted position.

4. In a shoe-stretcher, a toe-stretching unit comprised of two sections connected by a horizontally disposed toggle, a heel unit, a vertically disposed toggle connecting each

- of said sections to said heel unit, said latter toggles being comprised of flexible metal members, a spreading member adapted to be moved between said sections, an adjusting screw attached to said member and carried by said heel unit for moving said member to adjust said sections laterally and in fan-like fashion, a rack and pinion carried by said heel unit and connected to said toe-stretching unit for adjusting said latter unit longitudinally, means for controlling the movement of said rack and pinion, and a latch for engaging said rack to lock said units in their longitudinally adjusted position.
5. In a shoe-stretcher, a unit comprised of two separable sections, connected at their forward ends by a hidden and horizontal toggle, said sections being formed to provide a wedge-shaped chamber between the same, a spreading member movable back and forth in said chamber, a heel unit, said sections and heel unit having aligned vertical slots, vertical toggles formed of thin and flexible metal members, mounted in said slots and connecting said sections separately to said heel unit, means carried by said heel unit, for adjusting said spreading member in said chamber, means adjustable longitudinally also carried by said heel unit and connected to one only of said sections, and means carried by said last section and extending behind the other section for effecting simultaneous movement of said sections as said longitudinally adjusted means is operated.
6. In a shoe-stretcher, a unit comprised of two separable sections connected at their forward ends by a hidden and horizontal toggle, said sections being formed to provide a wedge-shaped chamber between the same, a spreading member movable back and forth in said chamber, a heel unit, said sections and heel unit having aligned vertical slots, vertical toggles formed of thin and flexible metal members mounted in said slots and connecting said sections separately to said heel unit, a member carried by said heel unit and connected to said spreading member for adjusting the same in said chamber, a rack and pinion construction carried by said heel unit and connected to only one of said sections, and a follower member carried by said latter section and extending behind the other sections for effecting simultaneous movement of said sections as said rack and pinion is operated.

7. In a shoe-stretching device, a toe-stretching unit comprised of separable sections, a heel unit, and a toggle connected to each of said sections, and separately connected to said heel unit, said toggles being formed of flexible metal members adapted to flex and permit ready and easy bodily and fan-like separation of said sections.

8. In a shoe-stretching device, a toe-stretching unit comprised of separable sections joined at one end only by a horizontal enclosed toggle, a heel unit, and a vertical toggle connected to each of said sections and separately connected to said heel unit, said toggles being operable in slots in the respective sections and heel unit portions and formed flexible metal members adapted to flex and permit ready and easy bodily and fan-like separation of said sections.

9. In a shoe-stretcher, a toe-stretching unit comprised of two sections separable bodily in a lateral direction and pivotally in fan-like fashion, a heel unit, and toggles connecting said sections to said heel unit, said toggles being formed of flexible members to readily permit of said lateral and flaring movements.

10. In a shoe-stretcher, a toe-stretching unit comprised of two sections separable laterally and longitudinally, a heel unit, means carried by said heel unit and cooperating with said sections to effect said lateral separation, means carried by said heel unit and connected to one of said sections for effecting longitudinal movement of said toe-unit, and means carried by said latter section and engaging the rear of the other section to effect simultaneous longitudinal movement of said sections.

11. In a shoe-stretcher, a toe-stretching unit comprised of two sections separable laterally and longitudinally, a heel unit, an adjusting member carried by said heel unit and cooperating with a device for effecting said lateral separation, a rack and pinion carried by said heel unit and connected to one of said sections for positively effecting longitudinal movement of said toe unit section, and means carried by said latter section and engaging the other section to effect simultaneous longitudinal movement of both said sections.

In testimony whereof, I have subscribed my name.

ANDREW KANELL.
